UNITED STATES PATENT OFFICE

1,999,357

CANNON

Louis L. Driggs, Jr., Tippecanoe City, Ohio, assignor to The Kilgore Mfg. Company, Westerville, Ohio, a corporation of Ohio

Application March 9, 1934, Serial No. 714,747

11 Claims. (Cl. 42—55)

This invention relates to improvements in cannons, and has for its object to provide a cannon barrel with a swinging breech-block adapted to support a pellet of carbide in such a position that water may be sprayed over its exposed surface.

It is an object of this invention to provide, in connection with a pellet of carbide, removably supported means supported adjacent the pellet for forcing a spray of water of measured quantity upon the pellet.

It is also an object of this invention to provide, in connection with the barrel of a cannon, means to support a pellet of carbide, and means to support adjacent the pellet of carbide a reservoir of water, together with means for spraying the water upon the pellet.

These and other objects and advantages will appear from the following description taken in connection with the drawing.

Referring to the drawing:

Figure 1 is a top plan view of the cannon with the projectile located in the end thereof.

Figure 2 is a vertical longitudinal section through the cannon shown in Figure 1.

Figure 3 is a section on the line 3—3 of Figure 2.

Figure 4 is a section on the line 4—4 of Figure 2.

The barrel 1 of the cannon is pivotally supported on a support 2 by means of trunnions 3, one on each side of the barrel. The outer end of the barrel is flared, as indicated by the numeral 4. The rear end of the barrel is closed by means of a breech-block 5 pivotally attached by means of a hinge 6 to the barrel and fastened in closed position by means of a catch 7, located on the top of the barrel.

In the inner surface of the breech-block is a pocket 8, lined by means of a cup 9 for containing a solid carbide pellet 10. Projecting downwardly from the interior of the barrel, at the top thereof and in front of the breech-block, is a projection 11 which has therein a water chamber 12 connected to a reservoir 13 by means of a passageway 14. The water chamber is provided with a rearwardly extending capillary opening 15 from which water is sprayed by means of a plunger 16 adapted to be moved up and down in the water chamber. The upper end of the plunger is reduced, as indicated by the numeral 17, and passes through a suitable opening provided in a plug 18 threaded in the upper end of the water chamber. On the upper end of the reduced part of the plunger is a head 19. Be-

tween the head and the plug is a spring 20, which tends to hold the plunger in its elevated position with a shoulder 21, formed by the reduced part 17, against the under surface of the plug.

When the plunger is in its elevated position the lower end thereof is in line with the upper surface of the passageway 14. It will be observed from an examination of Figure 2 that the capillary opening is beneath the passageway 14 so that whenever the plunger is lowered a definite quantity of water is forced out through the capillary opening and sprayed upon the surface of the carbide pellet. The amount of water sprayed is definite and is determined by the length of the stroke of the plunger or by the distance between the top of the passageway 14 and the bottom of the capillary opening 15.

The projectile 22 is adapted to fit in the flared-out part 4 of the end of the barrel. After the gas has been produced by spraying water upon the surface of the carbide pellet, suitable means is provided for igniting the gas, such as an igniter 23, preferably located just in front of the projection 11. The water used in connection with the production of the gas is placed in the reservoir, which has an opening in the top of the barrel easily accessible for receiving the water. The water in the reservoir is protected from any contaminating influence due to the explosion or burning of the gas.

None of the burned or exploded gases can enter into either the water chamber or the reservoir just as long as the plunger is down, and even when the plunger is up the water in the reservoir cannot become contaminated by the burning gases because of the remoteness of the reservoir from the capillary opening 15, and because of the smallness of this opening. By means of the accurate control of the amount of water the amount of gas produced is definite. No unnecessary consumption of the carbide results, and there is no excess of water to form a deposit on the carbide pellet.

It will be understood that I desire to comprehend within my invention such modifications as come within the scope of my claims and my invention.

Having thus fully described my invention, what I claim as new and desire to secure by Letters Patent, is:

1. In a cannon, a barrel having a breech-block with means thereon for holding a pellet of carbide, a projection in the barrel having therein a water reservoir and a water chamber connected to the reservoir by a passageway and having an

opening adjacent the carbide, and means for forcing water from the chamber through the opening onto the carbide.

5 2. In a cannon, a barrel having a breech-block with means thereon for holding a pellet of carbide, a projection in the barrel having therein a water reservoir and a water chamber connected to the reservoir by a passageway and having an opening adjacent the carbide, and a plunger in the chamber for forcing water from the chamber through the opening onto the carbide.

10 3. In a cannon, a barrel having a breech-block with means thereon for holding a pellet of carbide, a projection in the barrel having therein a water reservoir and a water chamber connected to the reservoir by a passageway and having an opening adjacent the carbide, and means for forcing water from the chamber through the opening onto the carbide, said passageway being located in the projection slightly above the opening.

15 4. In a cannon, a barrel having a breech-block with means thereon for holding a pellet of carbide, a projection in the barrel having therein a water reservoir and a water chamber connected to the reservoir by a passageway and having an opening adjacent the carbide, and a plunger in the chamber for forcing water from the chamber through the opening onto the carbide, said passageway being located in the projection slightly above the opening.

20 5. In a cannon, a barrel having a breech-block with a pocket therein for receiving a pellet of carbide and a projection adjacent the pocket, said projection having therein a reservoir and a water chamber connected to the reservoir and having an opening leading toward the pocket, and means to force water from the chamber through the opening.

25 6. In a cannon, a barrel having a breech-block with a pocket therein for receiving a pellet of carbide and a projection adjacent the pocket, said projection having therein a reservoir and a water chamber connected to the reservoir and having an opening leading toward the pocket, and means to force water from the chamber through the opening, said means consisting of a plunger.

30 7. In a cannon, a barrel having a breech-block with a pocket therein to receive a pellet of carbide and a projection having therein a water reservoir, a water chamber, a passageway from the reservoir to the chamber and an opening from the chamber toward the pocket, said opening being beneath the passageway, and a plunger in the chamber adapted to close the passageway and

force the water from the chamber through the opening onto the carbide in the pocket.

8. In a cannon, a support, a barrel pivotally mounted adjacent one end on the support, a breech-block on said end of the barrel, said breech-block having a pocket therein for holding carbide, a projection extending downwardly in the barrel between its point of pivot and the breech-block, said projection having therein a water reservoir extending from the top of the barrel to a point near the bottom of the projection, and a water chamber connected to the reservoir by a passageway and having an opening extending toward the pocket, and a plunger in the chamber adapted to close the passageway and force the water in the chamber through the opening.

9. In a cannon, a support, a barrel pivotally mounted adjacent one end on the support, a breech-block on said end of the barrel, said breech-block having a pocket therein for holding carbide, a projection extending downwardly in the barrel between its point of pivot and the breech-block, said projection having therein a water reservoir extending from the top of the barrel to a point near the bottom of the projection and a water chamber connected to the reservoir by a passageway and having an opening extending toward the pocket, and a plunger in the chamber adapted to close the passageway and force the water in the chamber through the opening, said water chamber having its upper end closed by a plug which serves to limit the upward movement of the plunger.

10. In combination in a cannon, of a cannon 35 barrel, means suspended within the cannon for containing liquid, said means having an access opening or supplying liquid from without the cannon, and means to force a spray of measured liquid from said means into the interior of the 40 cannon.

11. A new article of manufacture for use as a liquid supply means for gas cannons comprising a casing having intercommunicating dual reservoirs, one of said reservoirs having an opening 45 communicating therewith from the exterior of the cannon at the top thereof and the other of said reservoirs having an opening communicating with the interior of the cannon at the bottom thereof, and a plunger in the second of said reservoirs adapted to shut off communication between said reservoirs and to eject the fluid from the 50 second reservoir into the cannon.
